[57] CLAIM

The ornamental design for a connector spool extension, as shown and described.

DESCRIPTION

FIG. 1 is a front elevational view of a connector spool extension showing our new design, it being understood that the broken lines are for illustrative purposes only and form no part of the claimed design;

FIG. 2 is a right side elevational view thereof;

FIG. 3 is a left side elevational view thereof;

FIG. 4 is a top plan view thereof; and,

FIG. 5 is a rear elevational view thereof.

FIG. 4

FIG. 3

FIG. 1

FIG. 2

FIG. 5
